UNITED STATES PATENT OFFICE.

MAURICE J. CLARK, OF CHICAGO, ILLINOIS, ASSIGNOR TO NORTHWESTERN ELECTRIC COMPANY, OF CHICAGO, ILLINOIS.

WINDING-REEL FOR DYNAMO-ELECTRIC-MACHINE COILS.

1,088,126.

Specification of Letters Patent.

Patented Feb. 24, 1914.

Application filed March 27, 1912. Serial No. 686,683.

To all whom it may concern:

Be it known that I, MAURICE J. CLARK, a citizen of the United States of America, and a resident of Chicago, county of Cook, 5 Illinois, have invented certain new and useful Improvements in Winding-Reels for Dynamo-Electric-Machine Coils, of which the following is a specification.

This invention relates to devices for winding coils for dynamo electric machines which heretofore have been formed on a forming block which is provided with a groove arranged to conform to the shape of the finished coil as it is to be used on the machine. 10 This method of winding coils has been found to be comparatively expensive, both in the initial investment, since a different block is required for each of the different sizes, and also because of the time and labor required 15 to wind wire in the slot to form a coil.

The present invention is designed to provide a simple and comparatively inexpensive device which is capable of having coils formed thereon quickly, and which is capable 20 of adjustment within certain limits for producing coils of different sizes.

The main objects of this invention are to provide an improved device for winding coils which are to be used on dynamo electric 30 machines; to provide a device of this kind wherein a coil may be wound in one plane and after winding have portions thereof distorted out of said plane to a form which will fit the slots; to provide improved means for 35 distorting the coil; to provide improved means for adjusting the device to vary the size of the coil; to provide improved means for gripping the coil during the forming thereof; to provide improved means for adjusting the size of said holding members to 40 permit of the formation of coils of different thicknesses; to provide improved means for insuring the alinement of said holding members in position for winding the coil; to provide 45 improved mechanism for obtaining the relative shifting in pairs of said holding members for distorting said coil; to provide improved means for tilting certain jaws when being shifted to distort the coil; to 50 provide improved means for obtaining the tilting of said jaws in relatively opposite directions; and to provide improved means for dismantling a part of the device for removing the coil.

An illustrative embodiment of this invention is shown in the accompanying drawings, in which:

Figure 1 is a plan view of a device constructed according to this invention, showing the parts in their respective positions for winding a coil. Fig. 2 is a sectional view taken on the line A—A of Fig. 1. Fig. 3 is an end elevation, some of the parts in the background being omitted. Fig. 4 is a side elevation of the device as shown in Fig. 1. Fig. 5 is a sectional elevation taken on the line B—B of Fig. 1, showing parts thereof in their shifted positions. Fig. 6 is an enlarged sectional detail of one of the pairs of stationary holding members. Fig. 7 is a side elevation of the same as viewed from the plane of the line C—C of Fig. 1. Fig. 8 is an end elevation, partly sectional, of same as viewed from the plane of the line D—D of Fig. 1. Fig. 9 is an end elevation of one of said holding members as viewed from the left of Fig. 1. Fig. 10 is a perspective view showing separated the jaws which constitute one of the pairs of shiftable holding members. Fig. 11 is a perspective view of a finished coil as wound and formed on the device.

In the construction shown in the drawings the supporting frame 1 has mounted thereon the transversely disposed holding members 2, 3, 4 and 5 respectively arranged in pairs at opposite sides of said frame, said pairs being substantially at right angles to each other. The holding members 4 and 5 are arranged to be shifted along said supporting frame in respectively opposite directions into and out of alined position with the holding members 2 and 3. Said holding members are also adapted to be tilted into and out of vertical position respectively with the shifting thereof into and out of said alined position. The supporting frame 1 is provided with an internally threaded head 6 by which the device is adapted to be secured to a rotary member, preferably in a horizontally disposed position, so that it may be rotated for the purpose of winding the coil onto the holding members 2, 3, 4 and 5.

The holding members 2 and 3 each comprises a pair of flanged members or jaws 7 and 8 mounted in opposed relation on the crosspiece 9, carried at the end of the bar

10. The jaw 7 is locked in position on the crosspiece 9 by means of a head 11, which is eccentrically carried on a stud 12 having a threaded engagement with a tapped hole eccentrically located in the end of the crosspiece 9. The head 11 may be turned to the position indicated in Figs. 6 and 9, whereupon the jaw 7 is locked in a fixed position upon the crosspiece 9, or it may be 15 turned to a position of registering alinement with respect to the crosspiece 9, whereupon the jaw 7 may be removed from the crosspiece. The jaw 7 and crosspiece 9 are respectively provided with co-acting keyway 13 and key 14 whereby the jaw is secured 20 against turning on the crosspiece 9. The jaw 7 and head 11 are respectively provided with co-acting shoulders 15 and 16, (Fig. 9) which serve to limit the rotation of the head 25 so as to stop cross-arm 17 in position to register with the keyway 13 so as to permit the removal of said jaw. The jaw 8 is adjustable on the crosspiece 9 toward and away from the jaw 7 by means of a threaded rod or bolt 18, partially housed in the crosspiece 9 and having a bearing in the disk 19 secured to the end of said crosspiece, as indicated in Fig. 6. There are no threads 30 on the crosspiece 9, but the jaw 8 is threaded to co-act with the threaded rod 18 so that the turning of the rod in its bearing 19, by means of the cross-arms 20, will cause the jaw to slide along the crosspiece 9, as determined by the direction of rotation of the 35 bolt 18. The bars 10 each have telescoping engagement with one of the arms or tubular members 21, rigidly secured at opposite sides of the frame 1, and the rods are secured in their desired positions by means of 40 pins 22 inserted into registering apertures in the bars 10 and arms 21.

The holding members 4 and 5 each comprises a pair of jaws 23 and 24 formed as shown in Fig. 10 and pivotally mounted on 45 slides 25 and 26 arranged on opposite sides of the frame 1. Ears 27 formed on the underside of the flange 28 of the jaws 23 are secured to lugs 29 on the slides 25 and 26 by means of pins 30. The jaws 24 are provided 50 at their ends with flanges 31 which are adapted to be clamped to the flanges 32 on the jaws 23, by means of bolts and nuts 33. The flanges 31 are provided with apertures which carry the respective bolts, and the 55 flanges 32 are provided with slots 34, in which the bolts are slidable for adjusting the jaws 23 and 24 toward and away from each other.

Shoes or cams 35 are fixed on opposite 60 sides of the frame 1 at both sides of the slides 25, and are tapered or beveled on the ends which face the direction of movement of the slides 25 and 26. These shoes 35 are designed to co-act with the under surface 65 of the flanges 28 of the jaws 23 so as to force

the holding members 4 and 5 into a vertical position when shifted into alinement with the holding members 2 and 3, and to permit the holding members 4 and 5 to be tilted from a vertical position when said holding members are shifted out of alinement with the holding members 2 and 3, as shown in Fig. 5.

The pivotal connection of the holding members 4 and 5 on the slides 25 and 26, and the arrangement and construction of the shoes 35, permit the holding members 4 and 5 to become tilted when shifted, due to the tension of the coil thereon, out of a vertical position in the same relative direction, that is, inwardly toward the vertical plane which the holding members occupy when in said alined position. It is, however, necessary to have one of the members tilted from the vertical in the opposite direction in order that the finished coil may properly fit the armature. For this purpose one of the holding members, as, for instance, holding member 4, is provided with a depending lug or shoulder 36, which is adapted to be engaged by a cam or bar 37, as shown in Fig. 5, when the holding members are shifted out of their alined position. The cam or bar 37 is mounted on the side of the supporting frame 1, and is provided with slots 38 for adjusting it along the frame 1 to accommodate the shifting of the members 4 and 5 as determined by the size of the coil to be made. If desired, there may be two of the lugs 36 and bars 37 arranged on opposite 100 sides of the frame 1.

The mechanism by which the slides 25 and 26 are shifted along the member 1 comprises racks 39 and 40 respectively secured to said slides, and a gear 41. The gear 41 is journaled at the ends of the arms 42, secured to and extending outwardly from the sides of the frame 1, and the shaft 43 has one end thereof squared as at 44, to receive a crank for operating the gear. A brace 45 is secured to the arms 42 and extends around the racks 39 and 40 so as to engage the outer faces thereof and insure proper meshing of the racks with the gear.

In order to secure the coil in the holding members 4 and 5 when the members are being shifted for distorting the coil, the jaws 23 and 24 are provided with shoulders 46 to which adjustable clamping members 47 are adapted to be secured. The clamping members each comprises a pair of arms 48 and 49, pivotally connected together at 50, and having their ends bent transversely inward. The arm 48 carries a threaded bolt 51 which is designed to force down upon the coil a 125 block 52, placed between the jaws 23 and 24.

The jaws 7 and 8 of the holding members 2 and 3 are cut away or faced off on respectively opposite sides, as at 53, so that when the holding members 4 and 5 are shifted out 130

of alined position the coil will bend over the rounded shoulders formed by the cut away portion of the jaws.

The operation of the device shown is as follows:—The device is placed upon a suitable rotary member, preferably one that is horizontally disposed, by screwing the head 6 onto the threaded end of said rotary member. The holding members 4 and 5 are shifted into an alined position with the holding members 2 and 3 by turning the gear 41. As the holding members 4 and 5 are shifted to said alined position, the shoes 35 co-act with the under face of the flanges 28 of the jaws 23, and cause the holding members 4 and 5 to be tilted into a vertical position. When the holding members are brought into alined position, the faces of the jaws 7 and 23 are all located in substantially the same plane. The jaws 8 and 24 of the respective holding members are then adjusted toward or away from the jaws 7 and 23, as determined by the thickness of the coil to be formed. After adjusting the distance between the jaws of all the holding members, the holding members 2 and 3 are shifted toward or away from the frame 1, as determined by the length of the coil to be formed. One end of the wire, from which the coil is to be formed, is temporarily attached to one of the holding members 2 or 3, and the device set in rotation. The wire is held by the operator so as to be successively wound into the holding members until a coil having the desired number of convolutions has been formed. The rotation of the device is then stopped and the wire cut and the end suitably attached to the same holding member to which the other end of the wire is connected preparatory to distorting the coil. The coil is then secured in the holding members 4 and 5 by placing the bar 52 upon the coil and setting the clamp 47 so that the ends of the arms 48 and 49 engage the shoulders 46 on the jaws 23 and 24. The threaded bolt is then turned down so as to urge the bar 52 firmly into contact with the coil. When the coil is ready to be distorted, the pins 22 are removed from the registering apertures in the bars 10 and arms 21, and a suitable crank is connected to the squared head 44 of the gear shaft 43 and the gear 41 is rotated in the direction indicated by the arrow 53 (Fig. 5). The rotation of the gear 41 causes the rack 39 to shift the slide 25 and its holding member 4 toward the head 6, and causes the rack 40 to shift the slide 26 and its holding member 5 in the opposite direction, away from the head 6. As the holding members 4 and 5 recede from engagement with the shoes 35, the tension of the coil tends to tilt the holding members out of vertical position inwardly toward the plane which they occupy when in said alined position with the holding members 2 and 3. However, by the en-

gagement of the shoulders 36 with the cams or bars 37, the holding member 4 is tilted in the opposite direction, or outwardly from said vertical frame, as the slide 25 approaches the limit of the travel to which it is intended to be shifted. During the shifting of the holding members 4 and 5 the length of the coil is shortened through the inward travel of the bars 10 into the arms 21. After the holding members 4 and 5 have been shifted to their respective limits, bands are secured around the convolutions of the coil so as to hold the coil intact. The coil being distorted, it is then ready to be removed from the device. To accomplish this the clamps 47 and bars 52 are removed from the holding members 4 and 5 and the heads or parts 11 on the respective holding members 2 and 3 are turned to their registering positions with the ends of the cross-pieces 9, whereupon the jaws 7 may be removed from said crosspieces 9. The coil may then be readily removed from the device, it being in the shape indicated in Fig. 11.

Although but one specific embodiment of this invention has been herein shown and described, it will be understood that numerous details of the construction shown may be altered or omitted without departing from the spirit of this invention as defined by the following claims.

I claim—

1. In a device of the class described, the combination of a rotatable supporting frame, a pair of holding members mounted on opposite sides of said frame in a plane transverse to the axis thereof and being movable only in said plane, a second pair of holding members mounted on said supporting frame transversely to the axis thereof and at right angles to said first pair, said other holding members being slidable along said frame with respect to said first pair of holding members, and means adapted to shift said second pair of holding members into and out of alined position with said first pair of holding members, for the purpose specified.

2. In a device of the class described, the combination of a rotatable supporting frame, a pair of holding members mounted on opposite sides of said frame in a plane transverse to the axis thereof and being movable only in said plane, a second pair of holding members mounted on said supporting frame transversely to the axis thereof and at right angles to said first pair, said other holding members being slidable along said frame with respect to said first pair of holding members, means for shifting said first pair of holding members in said plane for adjusting the distance between them, and means adapted to shift said second pair of holding members into and out of alined

position with said first pair of holding members, for the purpose specified.

3. In a device of the class described, the combination of a rotatable supporting frame, a pair of holding members mounted on opposite sides of said frame transversely to the axis thereof, a second pair of holding members mounted on said supporting frame transversely to the axis thereof and at right angles to said first pair, said other holding members being slidable along said frame with respect to said first pair of holding members, and means adapted to shift said second pair of holding members 15 in respectively opposite directions into and out of alined position with said first pair of holding members, for the purpose specified.

4. In a device of the class described, the combination of a rotatable supporting frame, plates slidably mounted on opposite sides of said frame, holding members carried by each of said plates and disposed transversely to the axis of said frame, other holding members supported on said frame, and means adapted to shift said plates in 20 respectively opposite directions to bring said first holding members into and out of alined position with said other holding members, for the purpose specified.

5. In a device of the class described, the combination of a rotatable supporting frame, plates slidably mounted on opposite sides of said frame, holding members carried by each of said plates and disposed transversely to the axis of said frame, other holding members supported on said frame, a rack secured to each of said plates, and gear mechanism adapted to engage said 35 racks for shifting said plates to bring said first holding members into and out of alined position with said other holding members, for the purpose specified.

6. In a device of the class described, the combination of a rotatable supporting frame, plates slidably mounted on opposite sides of said frame, holding members carried by each of said plates and disposed transversely to the axis of said frame, other holding members supported on said frame, a rack secured to each of said plates, a gear 45 mounted between said racks and adapted to be operated for shifting said plates in respectively opposite directions for bringing the holding members carried thereby into and out of alined position with said other holding members, for the purpose specified.

7. In a device of the class described, the combination of a supporting frame, holding members mounted in pairs on respectively opposite sides of said supporting frame, means for shifting one pair of said holding members into and out of alined position with the other said holding members, and means adapted to tilt said shiftable holding 60

members respectively into and out of a vertical position when shifted into and out of alinement with said other holding members, for the purpose specified.

8. In a device of the class described, the combination of a rotatable supporting frame, a pair of plates slidably mounted on opposite sides of said frame, holding members pivotally mounted on each of said plates transversely to the axis of said frame, other holding members secured to said frame at right angles to said first holding members, means adapted to shift said plates so as to bring said first holding members into and out of alined position with said other holding members, and means adapted to tilt said shiftable holding members respectively into and out of a vertical position when shifted into and out of alined position with the said other holding members, for the purpose 80 specified.

9. In a device of the class described, the combination of a rotatable supporting frame, a pair of plates slidably mounted on opposite sides of said frame, holding members pivotally mounted on each of said plates transversely to the axis of said frame, other holding members secured to said frame at right angles to said first holding members, means adapted to shift said plates so as to bring said first holding members into and out of alined position with said other holding members, and means adapted to tilt said holding members in respectively opposite directions into and out of a vertical position 90 when said members are shifted into and out of said alined position, for the purpose specified.

10. In a device of the class described, the combination of a rotatable supporting frame, a pair of plates slidably mounted on opposite sides of said frame, holding members pivotally mounted on each of said plates transversely to the axis of said frame, other holding members secured to said frame at right angles to said first holding members, means adapted to shift said plates so as to bring said first holding members into and out of alined position with said other holding members, and shoes carried by said supporting frame and adapted to engage said holding members for shifting them into a vertical position when shifted into alinement with said other holding members and adapted to permit said holding members to be tilted out of vertical position when said holding members are shifted out of said alined position, for the purpose specified.

11. In a device of the class described, the combination of a rotatable supporting frame, a pair of plates slidably mounted on opposite sides of said frame, holding members pivotally mounted on each of said plates transversely to the axis of said frame, other holding members secured to said frame at 125

right angles to said first holding members, means adapted to shift said plates so as to bring said first holding members into and out of alined position with said other holding members, shoes carried by said supporting frame and adapted to engage said holding members for shifting them into a vertical position when shifted into alinement with said other holding members, and adapted to permit said holding members to be tilted out of vertical position when said holding members are shifted out of said alined position, and co-acting shoulders carried by one of said holding members on said frame and adapted to tilt said one holding member out of a vertical position in a direction opposite the tilting of the other said member, for the purpose specified.

12. In a device of the class described, the combination of a rotatable supporting frame, a pair of plates slidably mounted on opposite sides of said frame, holding members pivotally mounted on each of said plates transversely to the axis of said frame, other holding members secured to said frame at right angles to said first holding members, means adapted to shift said plates so as to bring said first holding members into and out of alined position with said other holding members, shoes carried by said supporting frame and adapted to engage said holding members for shifting them into a vertical position when shifted into alinement with said other holding members and adapted to permit said holding members to be tilted out of vertical position when said holding members are shifted out of said alined position, and co-acting shoulders carried by one of said holding members on said frame and adapted to tilt said one holding member out of a vertical position in a direction opposite the tilting of the other said member, said co-acting shoulders being relatively shiftable longitudinally of said supporting frame, for the purpose specified.

13. In a device of the class described, the combination of a rotatably supporting frame, a pair of plates slidably mounted on opposite sides of said frame, holding members pivotally mounted on each of said plates transversely to the axis of said frame, other holding members secured to said frame at right angles to said first holding members, means adapted to shift said plates so as to bring said first holding members into and out of alined position with said other holding members, shoes carried by said supporting frame and adapted to engage said holding members for tilting them into a vertical position when shifted into alinement with said other holding members, a lug on one of said holding members, and a bar on said supporting frame adapted to engage said lug for shifting said one holding member out of the vertical position con-

trary to the normal tension thereon, said bar being adjustable along said holding member.

14. In a device of the class described, the combination of a rotatable supporting frame, oppositely disposed arms mounted on said supporting frame transversely to the axis thereof, a crosspiece carried by each of said arms, a jaw removably mounted on one end of said crosspiece, means for locking said jaw in fixed position thereon, a second jaw slidably mounted on the opposite end of said crosspiece, means for adjusting said second jaw toward and away from said first jaw, said arms comprising parts having telescoping engagement whereby said jaws may be adjusted toward and away from each other, and a pair of holding members slidably mounted on said supporting frame and adapted to be shifted into and out of alined position with the said jaws, for the purpose specified.

15. In a device of the class described, the combination of a rotatable supporting frame, a plurality of holding members mounted on said supporting frame transversely to the axis thereof, and relatively shiftable in pairs into and out of alined position, means adapted to cause the relative shifting of said holding members into alined position to permit a coil of wire to be wound thereon, and to cause the relative shifting of said members out of alined position after said coil has been wound thereon, and means for securing the coil in said shiftable holding members, during the shifting thereof out of said alined position.

16. In a device of the class described, the combination of a rotatable supporting frame, a plurality of holding members mounted on said supporting frame transversely to the axis thereof and relatively shiftable in pairs into and out of alined position, means adapted to cause the relative shifting of said holding members into alined position to permit a coil of wire to be wound thereon, and to cause the relative shifting of said members out of alined position after said coil has been wound thereon, shoulders on said shiftable holding members, and adjustable clamps adapted to be set to engage said shoulders for securing the coil in said shiftable holding members during the shifting thereof out of said alined position.

17. In a device of the class described, the combination of a rotatable supporting frame, arms mounted on opposite sides of said supporting frame transversely to the axis thereof, a crosspiece carried by each of said arms, a removable jaw adapted to be mounted on one end of said crosspiece so as to have the outer face thereof substantially flush with the end of said crosspiece, a part eccentrically pivoted on the end of

said crosspiece and adapted to be shifted to an eccentric position with respect thereto for locking said jaw on said crosspiece, and to be shifted to a registering position with respect to said crosspiece for permitting the removal of said jaw; a second jaw slidably mounted on the opposite end of said crosspiece, means for adjusting said second jaw toward and away from said first jaw, and a pair of holding members slidably

mounted on said supporting frame and adapted to be shifted into and out of aligned position with said jaws, for the purpose specified.

Signed at Chicago this 11th day of March 15 1912.

MAURICE J. CLARK.
